UNITED STATES PATENT OFFICE.

RICHARD JUDD, ERNEST TAYLOR, AND RALPH S. MCNANEY, OF DOWAGIAC, MICHIGAN, ASSIGNORS TO PREMIER WARM-AIR HEATER COMPANY, OF DOWAGIAC, MICHIGAN, A CORPORATION OF MICHIGAN.

ADDITIONAL AIR SUPPLY FOR WARM-AIR FURNACES.

Application filed January 24, 1927. Serial No. 163,220.

This invention relates generally to warm air furnaces and refers more particularly to means for insuring the complete combustion of the fuel of such furnaces. One of the principal objects of the present invention is to provide means for directing warm air to the top of the combustion chamber in such a manner that it will be completely mixed with the incompletely burned products of combustion. Another object is to provide a furnace in which the means for heating the air and for directing the same to the combustion chamber, is built into the furnace and forms a component part thereof. With these and other objects in view, the invention resides in certain novel features of construction, combinations and arrangements of parts as will be more fully described and particularly pointed out in the appended claims.

In the drawings:

Figure 1 is a front elevation of the furnace with the fuel door in open position;

Figure 2 is a sectional view of the furnace. In the drawings wherein like characters of reference indicate like parts, the numeral 1 designates a warm air furnace built in accordance with our invention in which 2 indicates the combustion chamber, 3 the fire box and 4 the grate mounted directly below the fire box. As shown the fire box 3 consists of upper and lower annular sections 5 and 6 respectively, the upper section being provided with spaced ribs 7, while the lower section is provided with spaced longitudinally extending pockets 8 open at their lower ends and having inner longitudinal apertures 9. With this arrangement some of the air entering the furnace below the grate will be directed into the pockets 8 and out through the apertures 9 into contact with the sides of the fuel bed and thus greatly increase the combustion of the fuel.

As shown the upper portion of the combustion chamber is rounded as at 10 and is provided with a central opening 11 for the passage of the gases to a radiator 12. There is also provided a lateral passage 13 communicating with the combustion chamber through which the fuel is introduced into

the furnace, this passage being provided with a door 14 at its outer end.

The furnace of the present invention is adaptable for the use of either hard or soft coal. It has been found that it is practically impossible to have complete combustion of soft coal, if it is burned in the usual manner with air being introduced from the bottom of the furnace only. Therefore, in the event that soft coal is to be used, means have been provided for introducing an auxiliary air supply into the top of the combustion chamber. It is very important that this additional air be in a heated condition when it enters the top of the combustion chamber so that it will produce secondary combustion. For accomplishing this we provide means for allowing the air to enter through the door 14 and travel in a circuitous path and finally escape into the top of the combustion chamber.

As shown the door 14 is provided with inner and outer walls 15 and 16 respectively, joined at their outer edges so as to form a chamber 17 within the door. Positioned between the walls 15 and 16 centrally of the door and rigidly secured to each wall is an inverted U-shaped member 18 surrounding an opening 19 in the outer wall 16 of the door chamber. A small door 20 is supported upon the outer wall 16 and is adapted to close the opening 19. At the upper end of the large door 14, the inner wall 15 is broken away to provide openings 21 and there are provided inwardly extending flanges 22 partially surrounding the openings 21 and which are adapted to cooperate with the outer end portions of channels 23 for forming continuous air passages to the combustion chamber when the door 14 is in closed position.

As shown the channels 23 are preferably cast integral with the furnace structure and are positioned at each upper corner of the lateral passage 13. When the door 14 is closed the flanges 22 are adapted to overlap the outer end portions of the channels 23 so as to provide a tight fit for preventing the escape of air.

The construction and arrangement is such that the U-shaped member 18 is adapted to

divide the chamber 17 into a pair of circuitous passages. When the small door 20 is held in open position, air from the exterior of the furnace will enter through the opening 19 and will be directed downwardly into the bottom of the chamber 17, then upwardly in a divided stream to the top portion of the chamber 17 and finally will pass in through the channels 23 to the top portion of the combustion chamber.

The air will be heated during its passage from the opening 19 in the door 14 so that when it escapes out of the inner end portions of the channels 23, there will be generated enough pressure for ejecting the warm air straight across the combustion chamber where it will impinge against the rounded portion 10 and will be directed downwardly in a swirling motion so as to thoroughly mix with the incompletely burned products of combustion.

The door 14 may be constructed as a single integral unit or as shown in the drawings it may be divided into upper and lower sections 24 and 25 if found desirable. Also any suitable means (not shown) may be used for automatically opening and closing the small door as is found desirable.

From the foregoing it will be apparent that we have provided an additional air supply for the furnace which makes it more efficient in operation because it materially helps combustion of the fuel and eliminates much of the smoke and soot incident to the burning of soft coal. As is also apparent, we have provided a construction which may be manufactured with the furnace as a whole and not as a separate attachment which must be applied to the furnace either when it is assembled or after the assembling operation has been completed.

While it is believed that from the foregoing description, the nature and advantage of our invention will be readily understood, we desire to have it understood that we do not limit ourselves to the specific construction herein shown and described and that such changes may be resorted to when desired as fall within the scope of the claims.

What we claim as our invention is:

1. In a warm air furnace, the combination of a combustion chamber, a fuel supply passage therefor, a door for said passage and means for directing a supply of air into said combustion chamber including a channel extending longitudinally of and cast integrally with the walls of said fuel supply passage at the top portion thereof and a cooperating channel in said door adapted to communicate with the aforesaid channel when the said door is in closed position.

2. In a warm air furnace, the combination of a combustion chamber, a lateral fuel supply passage therefor, longitudinally extending channels located therein and having

their inner end portions opening into the combustion chamber, a door for said fuel supply passage having spaced walls forming a chamber provided with a centrally disposed opening in its outer wall, an inverted U-shaped member secured to the walls of said door chamber and surrounding said opening and forming with the walls of said door, a pair of air passages, the upper portions of the inner wall of said door chamber being provided with openings adapted to register with the outer end portions of the channels of said fuel supply passage to form therewith circuitous air passages when the said door is in closed position.

3. In a warm air furnace, the combination of a combustion chamber, a lateral fuel supply passage therefor, longitudinally extending channels located therein and having their inner end portions opening into the combustion chamber, a door for said fuel supply passage having spaced inner and outer walls forming a chamber provided with a centrally disposed opening in its outer wall, an inverted U-shaped member secured between the walls of said door chamber and surrounding said opening and having the legs thereof spaced from the bottom and sides of the door chamber and forming therewith separate passages for the incoming air, the upper portions of the inner wall of said door chamber being provided with spaced openings adapted to register with the outer end portions of the fuel supply channels when the said door is in closed position.

4. In a warm air furnace, a substantially cylindrical combustion chamber having the upper portions of its walls curved inwardly, a fuel supply passage for said combustion chamber, a door for said passage having an air passage therein, a channel extending longitudinally of the top portion of said fuel supply passage and having its outer end portion communicating with the air passage in said door, the inner end of said channel opening into the combustion chamber opposite a portion of the upper curved surface thereof, whereby the warm air escaping from said channel will travel across said combustion chamber and impinge against the said curved surface and will be directed downwardly in a swirling motion so as to thoroughly mix with the incompletely burned products of combustion.

5. In a warm air furnace, a substantially cylindrical combustion chamber having the upper portions of its walls curved inwardly, a fuel supply passage for said chamber, a door for said passage having air passages therein, a pair of spaced channels extending longitudinally of the top portion of said fuel supply passage at each side thereof and having their outer end portions communicating with the air passages in said door,

the inner end portions of said channels opening into the combustion chamber opposite portions of the upper curved surfaces thereof whereby the warm air escaping from said channels will impinge against the curved surfaces and will be directed downwardly in a swirling motion so as to thoroughly

mix with the incompletely burned products of combustion.

In testimony whereof we affix our signatures.

RICHARD JUDD.
ERNEST TAYLOR.
RALPH S. McNANEY.
